UNITED STATES PATENT OFFICE.

JAMES B. HOYT, OF TROY, NEW YORK.

HORSE-BOOT.

SPECIFICATION forming part of Letters Patent No. 398,834, dated March 5, 1889.

Application filed June 7, 1888. Serial No. 276,297. (No model.)

To all whom it may concern:

Be it known that I, JAMES B. HOYT, of the city of Troy, county of Rensselaer, and State of New York, have invented a new and useful Improvement in Calking-Boots for Horses, of which the following is a specification.

My invention relates to certain improvements upon "the calking-boot for horses" for which Letters Patent were granted to me October 4, 1887. This class of devices is made to cover and protect the hoofs of animals from calking; and the object of my improvement is to better adapt these calking-boots for wear and for attachment and detachment.

Accompanying this specification, to form a part of it, there is a sheet of drawings containing three figures illustrating my invention, with the same designation of parts by letter-reference used in all of them. Of these illustrations, Figure 1 is a perspective of my improved calking-boot, with what is the front when worn turned toward the sight. Fig. 2 is another perspective of the boot with what is the rear part turned toward the sight. Fig. 3 is a section of the boot taken on the line *x* *x* of Fig. 1.

The several parts of the calking-boot thus illustrated are designated by letter-reference, and the function of the parts is described as follows:

The letter *A* designates the upper or body part of the boot, which is made of thin sheet-steel or other similarly-elastic sheet metal, which is curved and drawn in at the top to nearly close around the ankle above the hoof, and therefrom is extended downwardly in a contour adapted to cover the front and sides of the hoof, leaving the back of the latter uncovered.

The letter *h* designates shoulders formed in the upper or body part, *A*, to adapt the latter to rest on the upper part of the hoof where the latter extends rearwardly.

Instead of the beaded edge formed in the top of the upper or body part, *A*, as illustrated in my older patent before named, I construct the body herein shown without said bead, and insert within the said top an interiorly-placed lining of hard rubber or leather, as indicated at *L*, which is made to extend downwardly

from the top of the body *A* a short distance, and upon the top of this lining I construct a bead, *B*, arranged to overlap the metal edge of the body and to outwardly subtend the latter thereat.

The letter *H* designates a hinged hasp that is attached to the body or upper *A* upon one side of its back opening, and this hasp has a slot, *S*, made in its outer end having an entering-eye, *e*.

The letter *P* designates a pin that is outwardly projected from the body part *A* at that side edge of the back opening in the latter which is opposite to that on which the hasp is placed, and the letter *B*² designates a button-form head upon the pin *P*, so that when the boot is applied to the hoof and the sides of the back opening are drawn together the hinged hasp is passed down over the button *B*, by means of the eye *e* in the end of the slot *S*, so that the narrow part of the slot will engage with the button-head to keep the parts connected.

The ring *L*, where lining the interior of the boot body or upper near its top edge, in connection with its beaded top *B*, where outwardly subtending the top metal edge of the body, makes the boot more comfortable to the foot, and the substitution of the ring *L* for the metal bead formed in the top of the sheet-metal body part makes the latter more elastic and easy of application. The substitution of the hinged hasp and pin for the slot and pin of the older method, though performing in reality the same office, enables the boot to be more easily attached and detached.

I am well aware that my invention herein is limited to and only has novelty when considered as an improvement upon the calking-boot for horses described in my older patent alluded to.

Having thus described my invention, what I claim, and desire to secure by Letters Patent, is—

In a calking-boot, the combination, with the upper or body part, *A*, made of sheet metal and adapted to fit the exterior of the hoof at the front and sides, of the non-metallic ring *L*, made to line the interior of the upper or body part near its top and having the

head B resting on the latter, and the hinged hasp H, made with the slot S', arranged on one of the rear side edges of the body part, and the pin P on the other side edge of the boot, substantially in the manner as and for the purposes set forth.

Signed at Troy, New York, this 29th day of

February, 1888, and in the presence of the two witnesses whose names are hereto written.

JAMES B. HOYT.
